UNITED STATES PATENT OFFICE.

HARRY E. McLAUGHLIN, OF LINCOLN, NEBRASKA.

GASOLENE-HEATER.

1,304,896.

Specification of Letters Patent. Patented May 27, 1919.

Application filed May 3, 1917. Serial No. 166,244.

To all whom it may concern:

Be it known that I, HARRY E. McLAUGHLIN, a citizen of the United States, residing at Lincoln, in the county of Lancaster and State of Nebraska, have invented a new and useful Gasolene-Heater, of which the following is a specification.

The subject of this invention is a heater for carbureters wherein a heating coil is 10 operatively associated with a carbureter to heat the contents thereof, and the objects of the invention are, first, to provide a heating coil with means for supplying the fuel thereto, and conveying the fuel therefrom to the carbureter, second, to provide means for circulating the fuel from the carbureter to the heating coil, and back to the carbureter, and, third, to provide a simple and efficient carbureter.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

One practical embodiment of the invention is shown in the accompanying drawing.

The drawing is a view in elevation and partly in section of a carbureter equipped with a heater in accordance with my invention.

Referring to the drawing by characters of reference, C denotes a carbureter, of any usual construction, which is provided with a float chamber 1, in which works the annular float 2, which operates, through the lever 3, an inlet valve 4.

The bottom of the float chamber 1 is drilled and tapped to receive a threaded end of suitable piping, indicated generally at 5, the other end of which piping is threaded into the tapped bore in the head 6 of a preferably vertically disposed cylinder 7. The upper end of the cylinder 7 is threaded internally to receive the plug 8 which forms

its other head. The plug 8 is drilled and 50 tapped to receive one threaded end of piping 9, the other end of which is threaded into a tapped bore formed in the side wall of the float chamber at the line of liquid level.

Within the cylinder 7 is a coil of wire 10, 55 along which are spaced globular insulating members 11. The ends of the coil of wire 10 are connected, through wires 12, which extend through insulating bushings 13, secured in apertures formed in the wall of the cylinder 7, to a suitable source of electrical supply, not shown. The coiled wire 10 is made of material of suitably high resistance to form a heating medium.

In use, the liquid fuel will fill the float 65 chamber, and heating attachment, and connecting pipes, up to the liquid level. Current is allowed to flow through the coil 10 which heats the fuel in the cylinder 7, causing the hot fluid to rise and flow into the 70 carbureter, and drawing cold liquid fuel from the carbureter to the heater. This sets up a circulation of the liquid fuel and keeps the contents of the float chamber at the proper temperature at all times.

Having described my invention, what I claim as new and desire to secure by Letters Patent, is:—

A carbureter, comprising a float chamber, means for admitting liquid hydro-carbon to 80 the float chamber, said float chamber provided with an outlet in the bottom thereof and an inlet in the side wall thereof, a cylinder beside the float chamber, a pipe leading from the outlet and communicating with the 85 cylinder through the lower portion thereof, another pipe leading to the inlet and communicating with the cylinder through the upper portion thereof, and a heating element in the cylinder.

In testimony that I claim the foregoing as my own, I have hereto affixed my signature in the presence of two witnesses.

HARRY E. McLAUGHLIN.
